UNITED STATES PATENT OFFICE.

NATHAN FRIEDMAN, OF NEW YORK, N. Y.

SELF-WINDING CLOCK.

1,091,500.

Specification of Letters Patent.

Patented Mar. 31, 1914.

Application filed April 20, 1912. Serial No. 692,034.

To all whom it may concern:

Be it known that I, NATHAN FRIEDMAN, a citizen of the United States, and resident of the borough of Manhattan, in the city 5 and State of New York, have invented a new and useful Improvement in Self-Winding Clocks, of which the following is a specification.

The object of my invention is to provide 10 a self-winding clock having a novel combination of co-acting elements for maintaining a predetermined tension of the main spring of the clock, the parts being so constructed, arranged and operated as to eliminate the difficulties now met with in clocks 15 of this character.

Another object of my invention is to provide 20 a self-winding clock which may be operated by an ordinary high voltage lighting current with perfect safety and utmost accuracy.

A practical embodiment of the invention is represented in the accompanying drawings, in which,

25 Figure 1 represents in front elevation, partly in section, a clock works with my invention applied thereto, the parts being shown in the positions which they assume when the electromagnet is deenergized.

30 Fig. 2 is a side view of the same. Fig. 3 is a fragmentary transverse section showing the parts in the position which they assume when the electromagnet is energized. Fig. 4 is a detail section showing the means for 35 adjusting the spring contact arm. Fig. 5 is a section through the main spring arbor, showing the switch for making and breaking the electric circuit, on an enlarged scale. Fig. 6 is an inverted plan view of the same.

40 Fig. 7 is a detail view showing the pawl and ratchet connection between the main spring arbor, the winding lever and the clock frame, Fig. 8 is a detail section taken from front to rear, through the clock works at 45 the main spring arbor, and Fig. 9 is a view in perspective of the switch.

The clock frame comprises the front and back plates 1 and 2, the bottom plate 3, and the spacing posts 4. The main spring 5 50 connects its arbor 6 and the gear wheel 7 of the clock works in the usual manner, the gear wheel 7 being loosely mounted on the main spring arbor. This main spring 5 is of sufficient length to insure the running of

the clock for a considerable period of time 55 should the electric connections be cut off by reason of some accident such, for instance, as the formation of a short circuit.

The hub 8 of the winding lever 9, which is herein shown as a wheel having a circumferential groove 10 in its rim, is loosely mounted on the main spring arbor 6. The hub 11 on the ratchet wheel 12, is fixed to the main spring arbor 6, and a spring pawl 13 carried by the winding lever serves to 60 rotate the arbor step by step as the winding lever is oscillated to wind the main spring 5 up to a predetermined tension and maintain it at such tension. A retaining pawl 14 carried by the clock frame engages the 65 ratchet wheel for preventing its reverse movement.

An electromagnet 15 of the solenoid type, is provided with a projecting screw-threaded end for its lining tube 16, to removably 70 secure the magnet to the bottom plate 3 of the clock frame. The insulated top of the magnet bears against the bottoms of the front and back plates 1 and 2 of the clock frame when the magnet is screwed up into 75 its position, thus truing the magnet and holding it rigidly in its trued position.

The armature 17 of the electromagnet 15, is suspended from the winding lever 9, by means of a cord 18, which winds into and 80 unwinds from the circumferential groove 10, as the lever is oscillated. A weight 19 is suspended from the other side of the winding lever 9, by means of a cord 20, which also winds into and unwinds from the circumferential groove 10. The weight 19 is sufficient to rock the lever 9 and thereby lift the armature 17, when the electromagnet is deenergized. By forming the winding lever 9 in the shape of a wheel, the 85 points of engagement of the cords 18 and 20, with the lever are kept at a constant distance from the axis of the lever as the lever is oscillated.

The hub 8 of the winding lever 9, has 100 fixed thereon a switch comprising an insulated member 21 and a conducting member 22. A spring contact arm 23 of conducting material is adjustably secured to a binding post 24 on an insulated plate 25 secured 105 to the back plate 2, at one side of the clock works frame. This spring contact arm 23 is connected to a source of electrical energy,

not shown herein, through a wire 26. The upwardly turned end 27 of the spring contact arm 23, is arranged to alternately engage the insulated member 21 and the conducting member 22 of the switch, the tension on the contact arm 23 being such that it tends to swing the free end 27 thereof laterally and radially toward the main spring arbor 6. The conducting member 22 is provided with a track 28 on its periphery along which the free end 27 of the contact arm 23 travels, as the switch is moving in its reverse direction. The insulated member 21 is provided with a track 29 and a retaining wall 30, along which the free end 27 of the contact arm travels when the switch is moving in its forward direction.

The arrangement of the parts is such that the free end 27 of the contact arm will snap 20 radially toward the main spring arbor from the track 29, on to the track 28, when the switch reaches the limit in its forward movement, and will snap laterally from the track 28 to the track 29, when the switch reaches 25 the limit in its reverse direction. A partition wall 30* is formed on the insulated member 21, between the tracks 28 and 29, for guiding the free end of the contact arm 23 along the said tracks intermediate the ends 30 thereof.

The clock works frame is connected to the source of electrical energy through the tubular core 16 of the electromagnet itself, the wire 31, the resistance 32, the fusible connection 33, the spring arm 34, and wire 35. A wire 36 also connects the clock frame with the resistance 32, the resistance 32 and the binding post 37 for connecting the spring arm 34 with the wire 35 being mounted 40 upon the insulated plate 25 hereinbefore referred to.

The resistance 32, usually of graphite, serves to prevent sparking between the spring contact arm 23 and the conducting 45 member 22 of the switch. The fusible connection 33 between the resistance 32 and the spring arm 34, will automatically release the arm 34 and thus break the circuit when the resistance 32 gets so hot as to melt this fusible connection. This could be caused by 50 some accident or disarrangement which would prevent the switch from working properly and permit the current to circulate through the electromagnet and resistance 32 55 without interruption for a short period. This melting of the fusible connection 33 will save the other parts of the apparatus from injury.

A stop 38 carried by the front plate 1 of 60 the clock works frame, coacts with a projection 39 on the rim of the winding lever 9, for limiting the rotary movement of the winding lever should the electric current be cut off through some accident. This stop 38 and

the projection 39 are so located with respect 65 to each other that the armature 17 is held within the effective field of the electromagnet, so that when the electric current is re-established, the movement of the armature can be controlled by said electromagnet. 70

The spring contact arm 23 is adjusted longitudinally as follows. The arm 23 is provided at its inner end with a screw-threaded portion 40 extended through the binding post 24. Lock nuts 41, 42, engage said screw-threaded end 40 of the contact arm upon opposite sides of the post 24. The arm 23 is held against rotative movement by means of a set screw 43.

In operation, presuppose the parts to be in 80 the position shown in Figs. 1 and 2 of the drawings. The free end 27 of the spring contact arm 23 has just snapped off the track 29 of the insulated member 21 onto the track 28 of the conducting member 22. This will 85 complete the circuit and will cause the energization of the electromagnet 15. The energization of the electromagnet will draw the armature 17 downwardly, thereby moving the winding lever and switch in a reverse direction and raising the weight 19. The free end 27 of the spring contact arm 23 will travel along the track 28 of the conducting member during this reverse movement of the lever and switch, until the end of the partition wall 30 is reached, when the free end of the contact arm will snap back from the track 28 of the conducting member, on to the track 29 of the insulated member. This will 90 break the circuit and cause the deenergization of the electromagnet 15, thus permitting the weight to rotate the winding lever and cause the free end of the spring contact arm to travel along the track 29, until it again snaps radially off the track 29 on to 95 the track 28, when the cycle of operations 100 will be repeated. If the current is cut off for a considerable period, the clock will keep on running, being driven by the tension of the main spring 4. When the current is on 110 again, the winding lever will be repeatedly oscillated until the main spring is wound up to the desired tension.

Some of the advantages obtained by the attachment herein described are the provision 115 of a very few moving parts for accomplishing the result desired; a very strong and simple switch which is not liable to get out of order; a noiseless mechanism; a sliding contact between the switch and its contact arm tending to keep the contact surfaces clean; the maintenance of a predetermined tension on the main spring for insuring an accurate running of the clock works; a small electrical current consumption; an 120 absolute safe apparatus because of the provision for preventing over-heating of the electromagnet; and the provision of means 125

for preventing sparking between the switch and contact arm irrespective of the strength of the electric current used.

What I claim is:

5. 1. An electrically controlled clock winding mechanism including in combination a frame, a main spring winding lever, mechanical and electrical means for oscillating the lever, a switch mounted on the hub of 10 the lever, comprising insulated and conducting members having separated tracks, the insulated member having a retaining wall and a partition wall both projecting radially beyond both tracks, and a spring contact 15 arm arranged to travel back along one of said tracks in engagement with said retaining wall and forward along the other of said tracks in engagement with said partition wall as the lever is oscillated and to 20 snap radially from the track on the insulated member to the track on the conducting member at the limit of the movement of the lever in one direction and to snap off the partition wall laterally from the track on 25 the conducting member to the track on the insulated member at the limit of the movement of the lever in the opposite direction.

2. An electrically controlled clock winding mechanism including in combination a 30 frame, a main spring winding lever, mechanical and electrical means for oscillating the lever, a switch mounted on the hub of the lever, comprising insulated and conducting members having separated tracks, the insulated member having a retaining wall and a partition wall both projecting radially beyond both tracks, and a spring contact arm 35 arranged to travel back along one of said tracks in engagement with said retaining wall and forward along the other of said tracks in engagement with said partition wall as the lever is oscillated and to snap radially from the track on the insulated member to the track on the conducting member 40 at the limit of the movement of the lever in one direction and to snap off the partition wall laterally from the track on the conducting member to the track on the insulated member at the limit of the movement of the 45

lever in the opposite direction, and means for 50 adjusting the spring contact arm longitudinally.

3. An electrically controlled clock winding mechanism including in combination a frame, a main spring winding lever, mechanical and electrical means for oscillating the lever, a switch mounted on the hub of the lever, comprising insulated and conducting members having separated tracks, the insulated member having a retaining wall 60 and a partition wall, a spring contact arm arranged to travel back and forth along said tracks in engagement with said retaining and partition walls, as the lever is oscillated, and to snap radially from the track on the insulated member to the track on the conducting member at the limit of the movement of the lever in one direction and to snap laterally from the track on the conducting member to the track on the insulated 65 member at the limit of the movement of the lever in the opposite direction, means for adjusting the spring contact arm longitudinally, and means for locking it in such adjustment. 70

4. An electrically controlled clock winding mechanism including in combination a frame comprising front and back plates and a bottom plate, a main spring winding lever, a suspended weight and a suspended armature and its electromagnet of the solenoid type for oscillating the lever, the said electromagnet having its lining tube screwed into the bottom plate and its top engaging the front and back plates for holding the 80 armature rigidly in position to permit the armature to slide freely therein and a switch for automatically making and breaking the circuit as the lever is oscillated. 85

In testimony that I claim the foregoing as 90 my invention, I have signed my name in presence of two witnesses, this eighteenth day of April 1912.

NATHAN FRIEDMAN.
